UNITED STATES PATENT OFFICE.

WILLIAM M. SMITH, OF WEST MERIDEN, CONNECTICUT, ASSIGNOR TO THE MERIDEN BRITANNIA COMPANY, OF SAME PLACE.

DESIGN FOR A COFFIN-SCREW HEAD.

Specification forming part of Design No. 7,797, dated October 13, 1874; application filed September 30, 1874.
[Term of patent 7 years.]

To all whom it may concern:

Be it known that I, WILLIAM M. SMITH, of West Meriden, in the county of New Haven and State of Connecticut, have invented a new Design for Coffin-Screws; and I do hereby declare the following, when taken in connection with the accompanying drawings and the letters of reference marked thereon, to be a full, clear, and exact description of the same, and which said drawings constitute part of this specification, and represent, in—

Figure 1, front view, and in Fig. 2 side view.

This invention relates to a design for the ornamental head of screws such as are used for securing the tops upon coffins; and the invention consists in the peculiar shape and configuration of the head of the screw, as shown in the accompanying illustrations.

The head consists of a square base, *a*, upon which is set a flat head rising from the base and gradually widening toward the top, then turning and forming a scallop, *d*, upon each side, thence inclining upward to a central scallop, *c*, all as shown in the accompanying illustrations.

The face of the head may be ornamented as shown or otherwise.

I claim—

A design for coffin-screw heads, substantially as shown in the accompanying illustrations.

WILLIAM M. SMITH.
